FURNITURE JOINT

Thomas James Turnell, Chigwell, England, assignor to Russell & Company (Furniture) Limited, London, England, a body corporate of Great Britain

Application October 3, 1952, Serial No. 312,875

4 Claims. (Cl. 155—196)

This invention relates to furniture and more especially to chairs, benches and other seats having four or more legs.

The invention has as one of its objects to provide an improved sturdy seat or other article of furniture which can readily be partially dismantled so as to occupy a minimum of space for storage or transit and can be easily and quickly reassembled for use.

According to the present invention the back and front portions or the side portions of the article are manufactured as frame-like permanent structures each having two or more legs, such structures being bridged by removable rails suitably locked in place when the article is assembled.

Preferably, in the case of a chair, the side rails are locked to the back and front portions and this may be effected by screw means and if desired also by interengaging dovetail or like formations, and additional detachable rails or bracing may be provided especially for the legs to enhance the rigidity of the assembled structure.

In a specific embodiment applied to a wooden chair, the front and rear seat rails incorporate at each end a metal plate at or near the base of a rectangular socket, such plates being furnished each with a tapped hole. Alternatively the plates may be located in the upper ends of the legs. On assembly each side rail is fitted into a front and rear socket and secured in position by bolts housed longitudinally in the rail and adapted to engage the respective tapped plates. The head of each bolt is accessible from a hidden recess on the underside of the rail and/or its inner face, and such head may be square or hexagonal or it may have a peripheral series of radial apertures for engagement by means of a tommy bar, these alternative forms of bolt head being conventional and therefore not shown.

In order to resist deformation due to the occupant of the seat leaning against its back, a bracing member may be mounted say in appropriate sockets in the legs of the chair beneath each side rail. Preferably, in order to obviate the necessity for separate locking means, such bracing members slant downwardly towards the rear so as to be forced into their sockets when rearward pressure is exerted on the chair back.

The front and rear seat rails together with the side rails constitute, when assembled, a four-sided framework for the support of a detachable seat member, cushion or cushion support, not shown.

In a further embodiment also applied to the chair, the front and rear seat rails carry corresponding pairs of tapped sockets or inserts, each pair co-operating, on assembly, with a connecting bar having its ends threaded with threads of opposite hand. On assembly, a pair of side seat rails are fitted into appropriate sockets in the front and back portions of the chair, while the connecting bars are rotated to draw the two portions together, turnbuckle fashion, and secure the side rails.

A preferred embodiment of the invention will now be

2

described by way of example with reference to the accompanying drawings in which:

Fig. 1 is a plan view of the chair frame.

Fig. 2 is a vertical section of the chair frame taken on the line II—II of Fig. 1.

Fig. 3 is a front elevation, and

Fig. 4 is an exploded detail view of one of the front leg corner joints.

Referring now to the drawings, a front permanent structure is formed by front legs 1 connected to a front rail 2 by mortice and tenon joints 3, 3A.

The corresponding rear permanent structure is constituted by rear legs 4 similarly secured to a rear rail 5, the rear legs being extended upwardly at 6 to support the back of the chair.

The front and rear structures are detachably connected by side rails 8 incorporating bolts 9 which engage registering bolt apertures 16 in the tenons 3 and plates 11 in the tenons 3 of the front and rear rails, the apertures 20 in the plates 11 being threaded. The bolts 9 engaging the apertures 16 serve to positively lock the tenons 3 in the mortices of the legs.

In particular, the side rails 8 have longitudinal cavities 13 on their inner faces through which the bolts 9 can be passed to apertures 14 in the ends of the side rails through which such bolts then project to engage corresponding apertures 15 in the permanent structures, the latter apertures communicating with the mortices 3A. Washers 10 are shown on the bolts 9 between the heads 30 thereof and the outer end walls of the cavities 13.

The threaded plates 11 may be secured in their tenons by glue or by any other suitable means so as to register accurately with the apertures 15 on assembly, it being understood that the mortice and tenon joints 3, 3A will 35 normally be also secured by gluing.

In order to strengthen the frame at the front angles, wooden detachable gussets 18 are provided having dovetail ribs 17 along their upper edges to engage corresponding dovetailed grooves 19 in the undersides of the respective side rails on assembly.

Before assembly of the chair the "gussets" or brackets 18 are assembled to the respective front legs by means of their stub tenons 20 glued into the mortices or the back faces of the front legs 1.

As will be appreciated, the main stresses that occur in chairs, e. g. due to the occupant leaning backwards, merely tend to urge the gusset into its correct assembled position.

As an optional addition to the gussets 18, rearwardly sloping bracing members 24 may be provided detachably with their ends received between inwardly facing cavities 25 in the front and rear legs.

It will be appreciated that the four rails 2, 5, 8 provide a locating frame for an appropriate seat cushion 55 which is not shown.

It will also be appreciated that the embodiments described may be applied without modification to a multi-seat bench, to a seat having no back, or even to a table having a separate top. Moreover, many of the locking 60 arrangements described may be applied to articles having more than two removable rails and/or more than four legs for example, a divan or bench having three pairs of legs bridged by three removable rails, while on the other hand the rails are not necessarily in the same planes as the legs.

While chairs or seats have been described that are divided transversely, and thus have front and back permanent structures, a chair or seat according to the invention may alternatively comprise a pair of permanent side structures connected by detachable transverse front and back rails.

In a modification of the invention the removable con-

necting rails, and it may be also, separate locking means such as the turnbuckle rod described above, may be pivotally attached to one of the permanent structures in order to prevent loss during transit and facilitate assembly.

By the present invention improved articles of furniture are provided which can be stored in a small space owing to the shallow frame-like nature of the permanent back and front or side structures employed.

What I claim is:

1. An article of furniture comprising frame-like permanent structures each including a pair of supporting legs, a transverse rail connecting the pair of legs, a mortice and tenon joint joining said rail at each end thereof to one of said legs, the mortice being in the leg and the tenon on one end portion of the rail, a metal plate in one element of the mortice and tenon joint having a tapped bolt aperture therein, and the leg having a bolt aperture therein extending transversely of and leading into the mortice in the leg from one side face of the latter, said last mentioned bolt aperture being in register with said tapped bolt aperture of the metal plate, and the tenon having a bolt aperture extending transversely thereof and located inwardly of the outer end of the tenon in register with the bolt aperture in said plate and the bolt aperture in the leg, and a pair of detachable transverse rails connecting said frame-like permanent structures, each of said detachable rails having at each end portion thereof inwardly of the outer end of the same a longitudinally extending cavity in a side face thereof, and a bolt aperture extending from the outer end wall of said cavity through the adjoining end portion of the rail to the adjoining outer end face thereof, and a threaded bolt extending through said last mentioned aperture and through the aperture in the leg and the aperture in the tenon, and in threaded engagement with the tapped aperture in the metal plate, the head of said bolt being disposed in said cavity, the length of the cavity being such as to provide for insertion of the bolt from said cavity

through the several bolt apertures when aligned for assembly, and the cross sectional size of the cavity being sufficiently larger than the bolt head to provide for turning the bolt relative to the rail to secure the parts together, said bolt by its engagement with the aperture in the tenon service to positively lock the tenon in the mortice of the leg.

5 2. An article of furniture of the construction defined in claim 1 and in which the longitudinal cavities in the 10 detachable rails are in the inner side faces of said detachable rails.

3. An article of furniture of the construction defined in claim 1 and in which the metal plate is in the tenon.

4. An article of furniture according to claim 1, the 15 longitudinal cavity in the front end portion of each of the detachable rails being in the inner side face of the same above the bottom face thereof, and each of said detachable rails having a dovetail groove in the under surface of its forward end portion below the longitudinal 20 cavity in said end portion, and a strengthening gusset projecting inwardly from the upper part of each of the forward legs, each of said gussets having a dovetail rib on the upper surface thereof to engage the dovetail groove in the under surface of one of said detachable rails.
